UNITED STATES PATENT OFFICE.

FRED ASHWORTH, OF BEVERLY, MASSACHUSETTS, ASSIGNOR TO UNITED SHOE MACHINERY CORPORATION, OF PATERSON, NEW JERSEY, A CORPORATION OF NEW JERSEY.

COP-WINDING MACHINE.

Application filed December 24, 1925. Serial No. 77,438.

The present invention relates to cop winding machines and is herein shown as embodied in a machine for winding flat disk shaped cops of waxed thread for use in dis-
5 coidal sewing machine shuttles.

The invention has been designed primarily as an improvement in cop winding machines of the type which comprise winding flanges between which the cop is wound, 10 a winding shaft upon which the cop is wound arranged concentric with the winding flanges, a driving shaft in alignment with the winding shaft, and means for moving the winding shaft into winding position 15 between the flanges and away from winding position so as to permit the completed cop to be removed from the machine. The object of the invention is to provide improved means for heating the various parts 20 of the machine with which the wax thread comes in contact and to provide means by which the completed cop may be more quickly and easily removed from the machine with less danger of deformation or 25 other injury. With these objects in view, the invention consists in the constructions, combinations and arrangements of parts hereinafter described and claimed.

In the accompanying drawings Fig. 1 is 30 a front elevation of a cop winding machine embodying the several features of the present invention; Fig. 2 is a side elevation of the machine; Fig. 3 is a front elevation partly in section of the winding instrumentalities; Fig. 4 is a section on line 4-4 of Fig. 3; Fig. 5 is a plan view of the parts shown in Fig. 3; and Fig. 6 is a perspective view of the completed cop.

The cop winding machine illustrated in 40 the drawings comprises a frame 8 which carries a wax pot 10 and winding instrumentalities, indicated generally at 12, to which the thread comes from the wax pot over a tension wheel 14 of the usual form, which is mounted on a bracket 16 adjustable 45 on a post 18 secured to the machine frame.

The winding instrumentalities, as shown in Fig. 3, comprise two winding flanges 20 and 22 between which the cop is wound, and 50 a winding shaft 24 concentric with the flanges. The flange 20 is formed integrally on a driving shaft 26 journaled in bearings 28 and 30 in axial alignment with the winding shaft and driven by a pulley 32 from a 55 treadle controlled source of power of any

usual or preferred form. The flange 22 has a hub 33 journaled in a bearing 34 and is restrained from axial movement by a set screw 36 engaging in an annular groove 38 of the hub. The winding shaft 24 is splined to 60 the hub 33 in order to permit relative longitudinal movement, and for the purpose of performing the winding operation is provided with a tongue 40 adapted to engage a slot 42 of the driving flange. The tongue 40 is 65 provided with a slot or groove 44 to receive the end of the thread and hold it during the winding operation. When the cop is completed the thread is cut and the winding shaft 24 is withdrawn from between the 70 flanges by means of a manually operated bell crank 46 pivoted to the machine frame and having a yoke 48 engaging a collar 50 on the reduced outer end 52 of the winding shaft. The bell crank is provided with a 75 stop member 54 which engages a detent 56 to hold the shaft in proper position during the winding operation and which is provided with a projection 58 adapted to engage the lower side of the detent to limit the 80 outward movement of the winding shaft when it is withdrawn from within the cop.

To facilitate the removal of the flat disk-like cop from between the winding flanges and avoid deformation and injury of the cop, a knock-off lever 60 is provided having a cop engaging surface 62 which extends between the winding flanges and which is curved to embrace the completed cop. This lever is pivotally mounted on the machine 90 frame and is provided with a handle extending within convenient reach of the operator. The lever is provided with a counter-weight 64 which normally holds the lever in the position shown in Fig. 4 in which the 95 surface 62 is out of engagement with the cop. A downward movement of the handle portion of the lever causes the surface 62 to engage the cop and remove it from between the winding flanges while exerting pressure 100 on a substantial portion of its periphery. During its removal therefore, the coils of thread of which the cop is composed are maintained in place by the winding flanges and by the knock-off lever so that each cop 105 as it is delivered is of uniform size and shape substantially as indicated in Fig. 6 of the drawings.

The wax pot is heated by an electrical heating unit 66 connected by an armored 110

cable 68 to a controlling rheostat 70 of any usual or preferred form, which in turn is connected by conductors 72 with any suitable power supply. Provision is also made for heating the winding instrumentalities and the tension wheel with which the thread comes in contact in order to prevent adhesion of the thread to any of these parts. The completed cop is merely a mass of thread, the turns being held together merely by the adhesion of the wax, and accordingly the parts of the machine which contact with the cop during the winding and removal operations are thoroughly heated in order that removal may be readily effected without deforming the cop. For this purpose the winding instrumentalities are heated by an electrical heating unit 74 which is enclosed in a block 76 secured between the bearings 28 and 34 so as to conduct heat from the heating unit to the bearings and thence to the winding flanges and the winding shaft. The cop engaging portion of the knock-off member when in inoperative position rests against the block 76 so as also to be conductively heated therefrom, thus eliminating the danger of the cop sticking to this part when the cop is removed from the machine. The unit 74 is energized by conductors 78 connecting with the supply conductors 72. The bracket 16, upon which the tension wheel 14 is mounted, is also provided with a heating unit indicated at 80 which serves to heat the bracket and by conduction to heat the tension wheel so as to prevent sticking of the thread to the wheel as it passes thereover. The unit 80 is energized by conductors 82 also connecting with the supply conductors 72. The current to all the heating units is controlled by a snap switch 82 of the usual form, and a lamp 84 is provided which gives a visible indication when the current is turned on.

The invention having been described, what is claimed is:

1. A cop winding machine having, in combination, two winding flanges between which the cop is wound, a driving shaft concentric with the flanges, a winding shaft in axial alignment with the driving shaft and longitudinally movable from winding position between the flanges to a position permitting discharge of the cop, and a knock-off lever arranged to be moved transversely between the winding flanges for discharging the cop.

2. A cop winding machine having, in combination, two winding flanges between which

the cop is wound, a driving shaft concentric with the flanges, a winding shaft in axial alignment with the driving shaft and longitudinally movable from winding position between the flanges to a position permitting discharge of the cop, a knock-off lever arranged to be moved transversely between the winding flanges for discharging the cop, and means for heating the knock-off lever.

3. A cop winding machine having, in combination two winding flanges between which the cop is wound, a driving shaft concentric with the flanges, a winding shaft in axial alignment with the driving shaft, bearings in which said shafts are mounted and in one of which the winding shaft is longitudinally movable from winding position between the flanges to a position permitting discharge of the cop, a knock-off lever arranged to be moved transversely between the winding flanges for discharging the cop, and an electrically heated block connected with the bearings and normally engaging the knock-off lever for conductively heating the parts which contact with the cop.

4. A cop winding machine having, in combination, two winding flanges between which the cop is wound, a driving shaft concentric with the flanges, a winding shaft in axial alignment with the driving shaft, bearings in which said shafts are mounted and in one of which the winding shaft is longitudinally movable from winding position between the flanges to a position permitting discharge of the cop, and an electrically heated block engaging the bearings and through the bearings heating the winding shaft and flanges.

5. A cop winding machine having, in combination, a wax pot, winding flanges between which the cop is wound, a driving shaft concentric with the flanges, a winding shaft in axial alignment with the driving shaft, bearings in which said shafts are mounted and in one of which the winding shaft is longitudinally movable from winding position between the flanges to a position permitting discharge of the cop, a tension wheel over which the thread passes from the wax pot to the winding shaft, an electrically heated bracket in which the tension wheel is mounted, and an electrically heated block engaging said bearings and through the bearings heating the winding shaft and flanges.

In testimony whereof I have signed my name to this specification.

FRED ASHWORTH.
